UNITED STATES PATENT OFFICE

JOSEPH JACOBS, OF BRIDGEPORT, CONNECTICUT, ASSIGNOR TO THE A. J. DONAHUE CORPORATION

SUSPENDERS

Application filed March 14, 1931. Serial No. 522,641.

This invention relates to an improvement in suspenders and particularly to suspenders adapted to be sold in separate units.

The object of this invention is to produce a suspender which may be separated into three units but which, when assembled, will provide the necessary rigidity and equal strain upon the connecting ends, and the invention consists in the construction as will be hereinafter described and particularly recited in the claims.

In the accompanying drawings:

Fig. 1 is a plan view showing a pair of suspenders constructed in accordance with my invention;

Fig. 2 is a sectional view taken on the line 2—2 of Fig. 1, enlarged;

Fig. 3 is a perspective view of the ends of the shoulder-straps and back-member separated from each other;

Fig. 4 is a perspective view of one form of coupling-member;

Fig. 5 is a plan view of a modified form of coupling-member; and

Fig. 6 is a sectional view taken on the line 6—6 of Fig. 5.

In carrying out my invention, I employ two shoulder-straps 10 and 11 formed from the usual suspender material, either elastic or non-elastic, and each provided with a tab 12 adjustably connected with the straps by buckles 13 of usual construction.

To the opposite ends of the straps are attached loops 14 and 15. These are formed from strips of leather or other suitable material, firmly stitched to the straps and so arranged that each loop has a fold which extends at an obtuse angle to the outer longitudinal edge of the shoulder-strap to which the respective loop is attached for the purpose as will hereinafter appear.

The back-member 16 is provided with the usual buttonhole-members 17 and is formed from the strip of material folded midway of its length, the ends being connected by the

buttonhole-members. The loops 14 and 15 and the loop of the back 16 are connected together by a metal coupling in the form of a loop.

As shown in Fig. 4, one member 18 may be tubular and the other member 19 of round wire, the two members bent into U-shape so that the ends of the wire may enter the ends of the tube.

In assembling the suspenders, one of the loops at the end of the shoulder-strap is inserted into the loop of the other strap and these two loops are connected with the back-member 16 by the coupling-member. In this way, the two loops of the shoulder-strap are brought into horizontal plane, from which the shoulder-straps extend forming a V and so that the strain is in a direct line upon the back-member.

Instead of forming the coupling-member as shown in Fig. 4, it may be formed as shown in Fig. 5 in which one U-shaped member 20 is formed from round wire and the other member 21 is also formed from wire, but with grooves 22 in its outer faces to receive the ends of the member 20. In either case, the coupling-member will retain its position by friction and this friction is increased by the strain upon the three straps of the suspenders.

I thus provide, in a very simple way, a pair of suspenders which may be separated into three units, but which, when connected together, will be in position to withstand the strain necessarily imposed upon them.

I claim:

1. A pair of suspenders comprising two shoulder-straps, each provided with a loop, each loop having a fold which extends at an obtuse angle to the outer longitudinal edge of the shoulder-strap to which the respective loop is attached, a back-member formed with a loop, and a coupling-member detachably connecting the shoulder-straps with the back-member.

2. A pair of suspenders comprising two shoulder-straps, each provided with a loop, each loop having a fold which extends at an obtuse angle to the outer longitudinal edge
5 of the shoulder-strap to which the respective loop is attached, a back-member formed with a loop, and a two-part separable coupling-member connecting the shoulder-straps with the back-member.

10 In testimony whereof, I have signed this specification.

JOSEPH JACOBS.
